MOUNTING MEANS FOR MANIFOLD
MACHINE CARBON PAPER

Laurence A. Petit, Chicago, Ill.

Application July 14, 1950, Serial No. 173,719

6 Claims. (Cl. 197—126)

1

This invention relates to a carbon paper support for use in manifold typewriters and the like and more particularly to a carbon pack supporting arm assembly.

An object of this invention is to provide an improved detachable supporting blade or arm for use in supporting carbon paper packs in manifold typewriting machines such, for example, as that shown in my issued Patent No. 2,236,155.

Still another object of this invention is to provide attaching means for a carbon pack supporting arm which may be readily disengaged from a supporting post to permit a quick removal of the arm and replacement of a new supply of carbon paper thereon.

A further object of the invention is to provide a supporting arm for carbon paper in a machine of the aforesaid type which will not necessitate separation of the plies of paper being typed in order to permit of the removal of the arm from and its reinsertion between plies of paper.

In accordance with the general features of this invention there is provided a manifold typewriter machine carbon paper supporting arm for lateral clamping engagement with a post at the side of the machine and provided on its supported end with latching means laterally engageable with the post without necessitating vertical movement of the arm in order to remove it from the post.

In accordance with other features of the invention there is provided a carbon pack supporting arm for a multi-fold typewriter machine, the arm having an opening in an edge portion thereof for laterally receiving a supporting post of the machine and latching means movable into the opening to hold and prevent the arm from coming off said post until the means is moved out of the opening.

Other objects and features of this invention will more fully appear from the following detailed description taken in connection with the accompanying drawing which illustrates a single embodiment thereof and in which

Figure 1 is a fragmentary plan view of a carbon paper supporting arm engaged with a post on the framework of a typewriting machine;

Figure 2 is a fragmentary side view, partly in section, taken on substantially the line II—II of Figure 1 looking in the direction of the arrows showing a plurality of supporting arms latched to the post;

Figure 3 is a fragmentary view, partly in section, taken from an underside of a supporting arm and more particularly on the line III—III

2

of Figure 2 and showing in dotted lines the disengaged position of the latching arm; and

Figure 4 is a cross-sectional view through the post assembly taken on the line IV—IV of Figure 2 looking in the direction indicated by the arrows.

As shown on the drawing:

The reference character 9 designates generally a portion of the framework of a manifold or multifold typewriter or billing machine. As shown in my aforesaid patent, it is old in the art to support on this framework 9 a plurality of vertically spaced carbon paper or pack arms which extend horizontally between the plies of paper in the machine. Such arms may extend from either or both sides of the machine between the plies of paper. I have designated my improved arm or blade by the reference character 10. Any suitable number of these arms may be employed and for purposes of illustration, I have shown two of them in the drawing (Figure 2).

The arms are all identical and are carried in vertical spaced relationship on a supporting post 11 fastened to the frame 9. Any suitable means 25 may be employed for securing the post 11 to the frame such, for example, as spaced studs 12 extending through spaced openings in the frame 9 and held in place by locking C-shaped washers 13. My present invention is not concerned with the manner in which the post 11 is fastened in place, but specifically with the manner in which the blades or arms 10 are detachably fastened to the post.

Heretofore it has been the practice to slide such arms vertically on the post 11, but I have found that this manner of attachment is disadvantageous in that it necessitates that the operator separate the plies of paper in order to permit of the vertical movement of the blades when it becomes necessary to remove them for any reason such, for example, as to replenish the supply of carbon paper carried by the blades or arms. In some instances, new packs are applied to the arms and in other instances the arms

40 must be disengaged to permit of the unwrapping of additional portions of carbon paper for insertion in the platen of the typewriting machine. I have designated generally by the reference character C a carbon pack carried by one of the arms 10 although it is to be understood that the carbon paper or pack may be of any suitable construction or arrangement, my invention being here concerned with the detachable engagement of the arm to the post and not specifically with

45 the construction of the carbon paper pack.

Since the blades or arms 10 are all identical, a description of one will suffice for all. Each arm or blade 10 has one of its longitudinal edges apertured to provide an opening 15 whereby the arm may be engaged around the post 11 to lock an edge of the post behind an abutment or shoulder 16 defining part of the opening 15 (Figure 3). This engagement of the arm with the post is effected when the latching arm 17 is in the dotted line position shown in Figure 3. The latching arm includes a cam portion 18 for bearing against an edge of the post 11 to hold the blade 10 on the post, as shown in full lines in Figure 3. The arm 17 is pivotally supported at 19 on the end portion 20 of the blade 10.

A tension spring 21 has one end anchored to the arm 17 and another to the blade 10 and is positioned to snap past the center line of the pivot 19 so as to hold the latching arm 17 in either engaged or disengaged position. In other words, it is a so-called dead center type of spring which upon movement past the dead center will operate in either direction to retain the arm 17 in whichever position it is moved.

In addition, I provide the underside of each blade 10 with a small right angle spacer 22, one leg of which is fastened to the blade and the other of which serves as a spacing means. Referring to Figure 2, it will be perceived that this spacer 22 serves to space the lower blade 10 from the frame 9 and in the case of the uppermost blade 10 spaces it from the immediately lower blade 10.

In the application of the blade 10 to the post 11, latching arm 17 is moved to the dotted line position shown in Figure 3 whereby the blade 10 can be laterally applied to the post 11. That is to say, the arm can be mounted on the post by a horizontal movement rather than having to be moved vertically. Once the blade 10 is positioned on the post with the post 11 behind the abutment or shoulder 16, movement of the latching arm 17 from the dotted line position to the full line position (Figure 3) results in the frictional binding of the blade and post together.

Removal of the blade is easily effected by snapping the latching arm 17 to the disengaged dotted line position (Figure 3) at which time the arm can be slid laterally off the post as the opening 15 is then available for the post to pass therethrough.

It will be understood that modifications and variations may be effected without departing from the scope of the novel concepts of the present invention.

I claim as my invention:

1. A manifold typewriting machine carbon paper supporting arm for lateral clamping engagement with a post on the side of the machine, said arm comprising a blade with an opening in an edge of the same so that the blade can be pressed laterally against the post to engage said blade with said post in said opening, and means for detachably binding said blade to said post when the post is inside said opening, said blade at said opening having an abutment for engaging around and over an edge of said post and said binding means being engageable with an opposite edge of said post to cooperate with said abutment in holding said blade on said post.

2. A manifold typewriting machine carbon paper supporting arm for lateral clamping engagement with a post on the side of the machine, said arm comprising a blade with an opening in an edge of the same so that the blade can be pressed laterally against the post to engage said

blade with said post in said opening, means for detachably binding said blade to said post when the post is inside said opening, and means for swinging said binding means under resilient pressure into and out of said binding position.

3. A supporting arm assembly comprising a blade-like arm having an aperture in a portion thereof, a supporting post positionable in said aperture upon relative horizontal movement of said arm and post, and means for detachably binding said arm to said post comprising a pivotal arm with a cam portion for frictionally bearing against the post when in gripping position and movable to a disengaged position by swinging of said pivotal arm whereby the blade-like arm can then be removed laterally from the post.

4. A supporting arm assembly comprising a blade-like arm having an aperture in a portion thereof, a supporting post positionable in said aperture upon relative horizontal movement of said arm and post, means for detachably binding said arm to said post comprising a pivotal arm with a cam portion for frictionally bearing against the post when in gripping position and movable to a disengaged position by swinging of said pivotal arm whereby the blade-like arm can then be removed laterally from the post, and spring means supported by said blade-like arm to be moved past dead center for holding the blade-like arm in engaged and disengaged positions.

5. A supporting arm assembly comprising a blade-like arm having an aperture in a portion thereof, a supporting post positionable in said aperture upon relative horizontal movement of said arm and post, and means for detachably binding said arm to said post comprising a pivotal arm with a cam portion for frictionally bearing against the post when in gripping position and movable to a disengaged position by swinging of said pivotal arm whereby the blade-like arm can then be removed laterally from the post, said aperture having a reduced area at one end defined by a shoulder and presenting an opening in an edge of the blade-like arm through which the post may enter the reduced area for disposition behind said shoulder.

6. A supporting arm assembly comprising a blade-like arm having an aperture in a portion thereof, a supporting post positionable in said aperture upon relative horizontal movement of said arm and post, and means for detachably binding said arm to said post comprising a pivotal arm with a cam portion for frictionally bearing against the post when in gripping position and movable to a disengaged position by swinging of said pivotal arm whereby the blade-like arm can then be removed laterally from the post, said aperture having a reduced area at one end defined by a shoulder and presenting an opening in an edge of the blade-like arm through which the post may enter the reduced area for disposition behind said shoulder, and said cam portion being movable into said opening to hold said blade-like arm with said post behind said shoulder and to prevent removal of the blade-like arm until said pivotal arm is pivoted to a disengaged position.
